J. T. BISHOP.
TORCH AND MELTING POT.
APPLICATION FILED MAY 18, 1917.

Patented Aug. 21, 1917.

INVENTOR:
Joseph T. Bishop.
By Almon Hall, Atty.

UNITED STATES PATENT OFFICE.

JOSEPH T. BISHOP, OF TOLEDO, OHIO, ASSIGNOR OF ONE-HALF TO HORACE BISHOP, OF TOLEDO, OHIO.

TORCH AND MELTING-POT.

1,237,460.

Specification of Letters Patent. Patented Aug. 21, 1917.

Application filed May 18, 1917. Serial No. 169,389.

To all whom it may concern:

Be it known that I, JOSEPH T. BISHOP, a citizen of the United States, residing at Toledo, in the county of Lucas and State of Ohio, have invented certain new and useful Improvements in Torches and Melting-Pots; and I do declare the following to be a full, clear, and exact description of the invention, such as will enable others skilled 5 in the art to which it appertains to make and use the same, reference being had to the accompanying drawings, and to the letters and figures of reference marked thereon, which form a part of this specification.

15 My invention relates to and is intended to provide a hand-ladle for Babbitt metal, solder, or the like, combined with a blow-torch adapted and arranged to melt the contents of the ladle, or to heat soldering irons, 20 or for directing a flame against any object, as may be required.

To these ends my invention consists of the devices and arrangement of parts herein-after described, and shown and illustrated 25 in the accompanying drawings, in which—

Figure 1 is a side-elevation of my device in central vertical longitudinal section; Fig. 2, a top-plan-view of the ladle hereinafter referred to, showing its pivoted support, 30 and Fig. 3, a front-elevation of the front supporting legs hereinafter referred to, with the projections thereon for supporting soldering irons or other objects to be heated.

Like numerals of reference indicate like 35 parts throughout the drawings.

In the drawings, 1 is a melting pot, shaped as a ladle, having a suitable pouring spout and provided at one side, at a right angle to the spout, with a lug 2 pivotally 40 connected with a corresponding lug 3 on a head 4, by means of a set-screw 5. The meeting faces of the two lugs are correspondingly indented so that when the screw 5 is set up the two lugs will engage each 45 other in such manner that the ladle can not be tilted on its pivot. By means of this pivotal arrangement the ladle may be tilted upwardly and inclined and secured as may be desired, and out of the way, as indicated 50 by the dotted lines in Fig. 1. The head 4 is chambered, as at 6, the chamber having a threaded opening for the reception of the forward end of horizontal pipe 7, having also, in its underside, a threaded opening 55 which takes a vertical pipe-connection 8.

The lower end of the pipe 8 is connected with and supports a burner or torch 9 discharging through the contracted transversely broadened orifice 10 and controlled by the usual needle-valve 11. Beneath the 60 torch is secured a shallow vessel 12 for the reception of the fluid which is burned to heat the torch to its proper ignition-point. Beneath the pot 1 is a chamber, formed either integral with the pot or by means of a 65 hood 13, secured by bolts and lugs, as at 14, to the under side of the pot. This chamber is open at its rear side so that the flame from nozzle 10 discharges directly into the chamber. The sides of the chamber may be 70 perforated as shown to permit the escape of the burned gases.

The pipe 7, at its rear end, is threaded into a hollow head 15 the chamber of which, at its lower part, is in communication with 75 a tubular reservoir 16 for the reception of gasolene or other burning fluid. This reservoir has an opening 17 with a suitable closure through which the fluid is introduced into the reservoir. On top of and connected with the chamber of the part 15 is a small air-pump 18, of any desired construction, for placing the contents of the chamber 80 16 and its connections under a suitable air-pressure.

85 The rear end of the reservoir 16 is provided with a handle 19 which may be conveniently grasped in one hand. Upon the pipe 7 is a sliding handle 20 adapted to be conveniently clasped by the other hand of 90 the operator. This handle should be constructed of some substance or in such manner that it does not readily become hot. It will be seen that by means of the two handles 19—20 the torch and ladle may be 95 lifted and carried, and that the sliding handle permits the hand to be advanced, as may be necessary, or to be withdrawn when the flame or heated portions are too hot for comfort.

100 In the under side of the head-piece 4 is a socket which receives the upwardly projecting pin 21 at the top of bifurcated piece 22 which piece forms a pair of legs which bestride the burner 10. Pivoted upon a lug 105 23 on the under side of the head 15 is a leg 24 which may be swung into either vertical or horizontal position. This leg is held in either position by means of a spring latch 25 arranged to engage one of the notches 110

26 on the head of the leg 24. These notches are disposed in such fashion that the latch will engage the appropriate notch when the leg is swung upwardly and backwardly or 5 downwardly into operative position. The bifurcated forward legs and the rear pivoted leg form a triangular support for the device which, while the heating is in progress, holds the several parts in proper op- 10 erative relation, but which, when the device is carried about, may be readily put out of the way. On each of the legs of the part 22 is a lateral projection or hook 27 which is designed to support one end of a solder- 15 ing iron, the forward end of the iron resting in the open mouth of the part 13.

The reservoir being filled and placed under pressure in the usual way and the torch being heated to the proper temperature from 20 the pan 12, in a manner which is well understood, the gasoline or other suitable fluidal fuel is admitted into the burner 10 by the valve 11 and the flame is projected into the chambered part 13, thus heating 25 the pot and its contents. When the metal in the pot is melted the device may be lifted by means of the two handles, the leg 24 is kicked into horizontal folded position and the ladle may now be conveniently carried 30 to the desired point and emptied. If the pot is not to be used it can be swung out of the way as above indicated or may be removed by withdrawing its pivot-pin. The front leg may be readily removed and the 35 device may be carried about and the flame employed as may be desired.

Having described my invention, what I claim and desire to secure by Letters Patent, is—

40 1. In a device of the character described, a melting-pot having therebeneath a chambered hood, a torch the flame of which discharges into the chamber of said hood, a reservoir, a pipe connecting the reservoir and the torch, a sliding handle on the pipe and a handle on the reservoir.

45 2. In a device of the described character, a torch, a reservoir, a pipe connecting the torch and the reservoir, a melting-pot piv- 50 otally and detachably connected with the pipe and in operative relation to the torch, and for the front and rear ends of the de- vice supports adapted to be moved into and out of operative position.

55 3. In a device of the described character, a front chambered head and a rear chambered head; a pipe connecting the chambers of said two heads, a torch connected with the chamber of the front head, a melting-pot 60 pivotally and detachably connected with said front head and in operative relation

to said torch, a reservoir connected with the chamber of the rear head, and means for placing the contents of the reservoir under pressure.

65

4. In a device of the described character, a front chambered head and a rear chambered head; a pipe connecting the chambers of said two heads, a torch connected with the chamber of the front head, a melting- 70 pot pivotally and detachably connected with said front head and in operative relation to said torch, a reservoir connected with the chamber of the rear head, means for placing the contents of the reservoir under 75 pressure, and supports connected with said front and rear heads and adapted to be thrown into and out of operative position.

75

5. In a device of the described character, a pair of chambered heads, a pipe connect- 80 ing the chambers of said two heads, a torch connected with the chamber of one of the heads, a melting-pot carried by said latter head and in operative relation to the torch, said pot having therebeneath a chambered hood into which the flame of the torch dis- 85 charges, a reservoir connected with the chamber of the other of said heads and means for placing the contents of said reservoir under pressure.

85

6. In a device of the described character, a chambered head, a horizontal feed pipe connected with the chamber of said head, a down-pipe connected at its upper end with said chamber and at its lower end being bent forwardly, a torch connected with the lower extremity of said down-pipe, a melting- 95 pot carried by said head and overhanging said torch, and supporting legs opera- 100 tively connected with said head.

95

7. In a device of the described character, a melting-pot, a torch disposed in opera- 105 tive relation to the pot, legs which support the pot and the torch, said legs having de- vices for the support of irons in operative relation to the flame of the torch.

100

8. A device of the described character comprising a front portion consisting of a melting-pot and a gasoline torch therefor; a rear portion consisting of a reservoir and an air-pump therefor; a straight pipe connecting said front and rear portions; removable supports for said front and rear portions; a handle on said rear portion, and a sliding handle on said straight pipe.

110

In testimony whereof I affix my signature in presence of two witnesses.

JOSEPH T. BISHOP.
